CLAIM

The ornamental design for a combination cap and sun hat, as shown and described.

DESCRIPTION

FIG. 1 is a side perspective view of a combination cap and sun hat showing our new design, the broken line showing of the human form is for illustrative purposes only and forms no part of the claimed design;

FIG. 2 is a rear perspective view thereof;

FIG. 3 is a front perspective view thereof;

FIG. 4 is a rear perspective view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is a front perspective view of a second embodiment of a combination cap and sun hat showing our new design, the broken line showing of the words “Your Logo” is for illustrative purposes only and forms no part of the claimed design.
